GERALDINE PHIN CLARK, OF VICTORIA, BRITISH COLUMBIA, CANADA

DUPLICATING MACHINE

Application filed July 10, 1928. Serial No. 291,516.

The invention is a duplicating machine that is easily and efficiently operated and particularly adaptable for small quantities of work.

- 5 The object of the invention is to provide a hand operated duplicating machine with resilient means for holding the platen a short distance above the paper when not printing.
- 10 Another object of the invention is to provide a simple and inexpensive duplicating machine which uses any standard stencil and turns out a clear copy.

Another object of the invention is to provide a duplicating machine in which the platen is not lifted during the operation.

Another object of the invention is to provide a duplicating machine in which the platen is readily inter-changeable without soiling the hands so that different colors may readily be used.

Another object of the invention is to provide a duplicating machine which is of a simple and durable construction, difficult to put out of order, and readily repaired.

Another object of the invention is to provide a duplicating machine in which the paper may be squared against the platen when the platen is in the position of rest.

30 A further object of the invention is to provide a duplicating machine which is portable, has very little weight and is readily carried by the handle by which it is operated.

35 A still further object of the invention is to provide a duplicating machine in which the platen may be readily removed and used for printing in books or upon other surfaces that cannot be placed in the machine.

40 And a still further object of the invention is to provide a duplicating machine that is of a simple and economical construction.

45 With these ends in view the invention embodies a duplicating machine having a base and a curved platen adaptable to hold a stencil, and in which the base is provided with resiliently held strips at the ends for supporting the platen a short distance above the surface thereof, with means for holding

the platen to the base while operating and means for holding the platen to the base when not in use.

Other features and advantages of the invention will appear from the following description taken in connection with the drawings, wherein:

Figure 1 is a view showing the device as it would appear in use.

Figure 2 is a view showing the machine with the platen in the position of rest between operations.

Figure 3 is a cross section through the machine showing the resilient members for supporting the platen and showing the platen resting upon these members.

Figure 4 is a plan view of the back of the platen.

Figure 5 is a cross section through the machine showing the parts in the same general arrangement as shown in Figure 3 and with the parts formed by sheet metal stampings.

In the drawings the device is shown as it would be made, wherein numeral 1 indicates the base, numeral 2 the platen, and numeral 3 a piece of paper that may be placed upon the base.

The base 1 may be made of a solid piece of material with rubber knobs 4 at the corners upon which it rests as shown and may be provided with a recess 5 in the center of the top in which a resilient backing as indicated by the numeral 6 is placed. It is understood however, that the pad 6 and the recess 5 may be omitted so that the paper may be placed directly upon the flat surface at the top of the base instead of upon the pad. Adjacent the ends of the base are slots 7 in which plates 8 are slidably mounted and the plates 8 are resiliently held upward by springs 9 in openings 10 as shown in Figure 3. At the lower ends of the openings 10 are plates 11 which are held by screws 12, and in the centers of these plates are adjusting screws 13 which are positioned so that they will extend upward through the springs to points 14 where they will limit the downward movement of the plates 8 when the plates are forced down.

ward by the platen. It will be understood that the springs 9 and screws 13 may be arranged in any suitable manner or any other suitable means may be used for resiliently holding the plates 8 in the upward position. The ends of the plates 8 are provided with projections 15 and 16 and it will be seen that the projections 15 engage the under side of extensions 17 at the top of one end of the slots 7 and the projections 16 engage plates 18 located at the opposite ends of the slots and held by screws 19, thereby providing means for limiting the upward movement of the plates 8. It will be observed that by removing the screws 19 and the plates 18 the plates 8 may readily be removed and also that by adjusting the screws 13 the downward movement of the plates 8 may readily be adjusted.

At the sides of the base 1 are bars 20 which are held to the base by screws 21 and provided with notches 22 at the opposite ends which engage screws 23 on the cover to lock the cover to the base when the device is not in use or when it is being carried. These bars may readily be released and moved downward to the position shown in Figure 1 when not in use. At the ends of the base are straps 24 through which bars 25 pass and one end of the bars is bent upward as indicated by the numeral 26 and the other end is pivotally mounted on pins 27 at the ends of the cover which is indicated by the numeral 28. These bars are so arranged that they will hold the cover and platen in the position of rest as shown in Figure 2 and at the same time slide through the straps to permit the platen to roll across the base when printing.

In the design shown in Figures 1 to 3 the cover is made of a flat piece of material with recesses at the edges and pins 29 in the center which engage slots 30 in plates 31 on the back of the platen 2. It will be observed that the platen may be placed against the cover and as it is moved toward one end the pins 29 will be placed into the slots 30 and hold the platen to the cover. In the design shown the platen 2 is made of a solid piece of material with a groove 32 in the center to clear the pins 29 and grooves 33 adjacent the sides in which the ends of the material covering the platen are held by bars 34 and the bars 34 are held by screws 35 as shown in Figure 4. It will be observed that the edges of the platen extend beyond the shoulders of the central part of the cover which are indicated by the numeral 36 and strips 37 are forced into the openings between the edges of the platen and the upper part of the cover to hold the edges of a stencil that may be placed upon the platen.

In this design the platen is covered with a piece of fabric which is saturated with

ink and the stencil is placed over the fabric so that if a sheet of paper as indicated by the numeral 3 is placed upon the base and the platen rolled across it a print will be placed upon the paper. The cover is provided with a handle as indicated by the numeral 38 and it will be observed that by gripping the handle and forcing the platen downward upon the base as it is moved across the machine the resiliently held bars 8 will move downward a sufficient distance to permit the platen to print and after the platen has been moved across the base the platen may be rolled back without being pressed downward as shown in Figure 3 so that it will be held above the paper and therefore will not blur the print. The weight of the platen is not sufficient to move the bars 8 downward so that the platen will only engage the paper when it is desired to make a print and at this time it should be held downward by the operator. In the design shown in Figure 5 the cover and base are stamped from sheet metal and the platen is made of a perforated plate 39 which is held on clips 40 extending downward from the cover and the stencil is held by strips 41 which are similar to the strips 37. The cover and base are otherwise similar to the design shown in Figure 3 with the pad 6 held in the recesses 5 and the bars 8 resiliently held and their downward movement limited by the screws 13.

The pad 6 and the recesses 5 may be omitted or the pad may be replaced by a wood panel, and in this design the platen is shown held to the base by the bars 20.

It will be understood that other changes may be made in the construction without departing from the spirit of the invention. One of which changes may be in the use of any other material and in the changing of the design to compensate for structural details necessitated by the change of material, another may be in the use of other means for resiliently holding the platen above the top of the base, another may be in the use of other means for attaching the platen to the base, another may be in the use of other means for attaching the platen to the cover and still another may be in the use of a platen of a different type.

The construction will be readily understood from the foregoing description. In use the device may be supplied as shown and it will be observed that with the platen in the position shown in Figure 2 a sheet of paper may be placed upon the pad 6 with the edge against the face of the platen so that the edge may readily be squared with the platen. The platen may be provided with an ink pad and a stencil as hereinbefore described and as it is rolled across the base and held downward the stencil will engage the paper and print upon it;

and then after the print is made the platen may be rolled back without being pressed downward so that it will ride upon the bars 8 and be held above the paper which will prevent reprinting and blurring and make it possible to release the platen upon the base without danger of the platen engaging the paper.

It will also be observed that by removing the bars 25 from the pins 27 the platen may be removed from the base and used to print upon the pages of a book or upon a window pane or any surface that cannot be placed upon the base of a machine.

Having thus fully described the invention, what I claim as new and desire to secure by Letters Patent is:—

1. In a device of the class described, a base, a cover, a curved platen removably attached to the cover, means adjacent the ends of the base for resiliently supporting the platen, means for holding the platen upright at one edge of the base, an ink pad on the platen, and means for holding a stencil over the said ink pad.

2. In a duplicating machine, a base, a slightly resilient pad on the base, bars adjacent the ends of the base, means for resiliently holding the bars upward, adjustable means for limiting the downward movement of the bars, a cover having a handle thereon, a platen removably attached to the cover, an ink pad on the platen, means for holding a stencil over the platen, means for supporting the platen in an upright position at one edge of the base, and means for holding the platen to the base when not in use.

3. In a duplicating machine, a base, bars adjacent the ends of the base, means for resiliently holding the bars upward, adjustable means for limiting the downward movement of the bars, a cover having a handle thereon, a platen, means for holding a stencil over the platen, means for supporting the platen in an upright position at one edge of the base, and means for holding the platen to the base when not in use.

4. In a duplicating machine, a base with a flat upper surface, transverse bars slidably mounted in slots adjacent the ends of the base and extending upward therefrom, springs below the bars for holding them upward, screws extending upward through the base to points below the bars to limit the downward movement of the bars, a platen adaptable to be rolled across the base and supported on the transverse bars, means on the platen for holding a stencil, and means in the platen for supplying ink to the stencil.

5. In a machine of the character described, a base, a platen adaptable to be rocked across the base, and means extending continuously across the base for resiliently supporting the platen a short distance above the base.

6. In a machine of the class described, a

base, a platen adaptable to rock across the base, means extending continuously across the base for resiliently supporting the platen a short distance above the base, and means for holding the platen in an upright position at the edge of the base.

7. In a device of the class described, a base, a curved platen, a cover to which the platen is removably attached, and means extending continuously across the base for resiliently supporting the platen a short distance above the base.

In testimony whereof I affix my signature.

GERALDINE PHIN CLARK.
